(57) **CLAIM**

The ornamental design for a confinement plate for a substrate processing chamber, as shown and described.

DESCRIPTION

FIG. 1 is a top, isometric view of a confinement plate for a substrate processing chamber, showing my new design;

FIG. 2 is a top plan view thereof;

FIG. 3 is a bottom plan view thereof;

FIG. 4 is a front elevation view thereof;

FIG. 5 is a rear elevation view thereof;

FIG. 6 is a right side elevation view thereof;

FIG. 7 is a left side elevation view thereof; and,

FIG. 8 is an enlarged cross-sectional view taken along line 16-16 of FIG. 10.

1 Claim, 5 Drawing Sheets
